UNITED STATES PATENT OFFICE.

HERBERT S. WHITING, OF HAWORTH, NEW JERSEY.

DESIGN FOR A LIGHTING FIXTURE.

Application filed July 29, 1924. Serial No. 10,309. Term of patent 7 years.

To all whom it may concern:

Be it known that I, HERBERT S. WHITING, a citizen of the United States, residing in Haworth, in the county of Bergen and State of New Jersey, have invented a new, original, and ornamental Design for Lighting Fixtures, of which the following is a specification, reference being had to the accompanying drawing, forming a part thereof, and which is a side elevation of a lighting fixture showing my new design.

I claim:

The ornamental design for a lighting fixture as shown.

HERBERT S. WHITING.
